No. 885,750.

PATENTED APR. 28, 1908.

A. F. HART.
TRACK TAMPING IMPLEMENT.
APPLICATION FILED JAN. 17, 1908.

UNITED STATES PATENT OFFICE.

ABLE F. HART, OF HICKORY, NORTH CAROLINA.

TRACK-TAMPING IMPLEMENT.

No. 885,750.

Specification of Letters Patent. Patented April 28, 1908.

Application filed January 17, 1908. Serial No. 411,345.

To all whom it may concern:

Be it known that I, ABLE F. HART, a citizen of the United States, residing at Hickory, in the county of Catawba and State of North Carolina, have invented a new and useful Track - Tamping Implement, of which the following is a specification.

This invention has relation to track tamping implements and it consists in the novel construction and arrangement of its parts as hereinafter shown and described.

The object of the invention is to provide an implement which may be readily used for the purpose of tamping and packing ballast under the cross ties of a railroad track and means is provided for fixing the implement with relation to the track and the tie during such operation.

The implement consists primarily of a wheel mounted axle which in turn supports suitable rack standards. Clamp members are hingedly attached to the lower ends of said standards and are adapted to be forced against the sides of the track rails and under the heads thereof for the purpose of fixing the implement with relation to the said rail. Arms are journaled at their inner ends to the axle and bars are carried by the outer ends of said arms. Sleeves are adjustably mounted upon said bars and tamping bits are adjustably positioned in the sleeves. Operating levers having segmental gear ends are adapted to operate against the opposite edges of the rack standards and when depressed bear against said bars for the purpose of forcing the same and the bits carried thereby in downward directions. Each lever is provided with a pawl which engages an aperture provided in the bar at a point immediately below the lever. Said pawls afford means for raising the bars and the bits as the levers are swung up.

The bits generally are arranged to move while tamping the ballast in planes parallel with the track but at points where the track rails intersect or cross the ties it is essential to so mount the tamping bits that they will operate in substantially oblique courses with relation to the track rails for the purpose of effectually tamping the ballast directly under the points of intersection of the ties and rail.

Other advantages incident to the arrangement of the parts of the tamping implement will appear as the several parts of the implement are described in detail.

In the accompanying drawing: Figure 1 is a transverse sectional view of the implement cut on the line 1, 1 of Fig. 2. Fig. 2 is a top plan view of the implement. Fig. 3 is a side elevation of a bit used upon the implement for tamping under the intersection of a rail and tie, and Fig. 4 is a plan view of the intermediate portion of a longitudinally extensible member for holding the clamps against the rails.

The implement consists of the axle 1 which is mounted upon the wheels 2, 2. The rack standards 3 are mounted at the end portions of the axle and are provided at their edges with the teeth 4. The clamp members 5 are hingedly attached to the lower ends of the standards 3 and are adapted to be forced into contact with the inner sides of the track rails 6 and below the heads thereof by means of the longitudinally extensible cross bar 7. As indicated in Fig. 4 the said bar 7 may be composed of telescoping sections which are moved longitudinally with relation to each other by means of the lever and cam mechanism 8. Thus, it will be seen that when the bar 7 is extended against the inner side of the clamp members 5 the said members are forced against the sides of the rails 6 and the tamping implement is fixed with relation to the rails. The arms 9 are journaled at the end portions of the axle 1 and the transversely disposed bars 10 are mounted in the said arms and lie upon opposite sides of the axle 1. The sleeves 11 are adjustably mounted upon the bars 10 and the bits 12 are adjustably mounted in the said sleeves 11. The levers 13 are provided at their ends with the gear segments 14. Said segments are adapted to adjustably engage the teeth 4 of the standards 3 and the said levers bear laterally against the bars 10 at the points 15. Each lever is provided with a pawl 16 which is adapted to enter a recess 17 provided in the bar 15. Thus it will be seen that when the gear segments 14 of the levers 13 are engaged with the teeth 4 of the standards 3 and the outer ends of the said levers are reciprocated vertically as the lever moves down it bears upon the upper side of the bar 10 which together with the bits 12 are correspondingly depressed. Thus, the lower ends of the bit 12 force the ballast material under the tie 18. When the outer end of the lever 13 is swung up the pawl 16 which is in engagement with the bar 10 carries the said bar and the attached bits 12 up. Thus, the bar and bits

are reciprocated by the movement of the levers. In order to regulate the extent of the thrust of the bits 12 the gear segments 14 may be so mounted upon the teeth 4 of the standards 3 as to cause the said bits to have major or minor thrust or movement under the tie 18.

In the present invention provision is made for tamping and packing the ballast material under a tie at the point of intersection of the track rail. The means for accomplishing this mode of tamping consists of the bits 19 which are connected by means of the ball and socket mechanism with the bars 10. Said bits 19 are located adjacent the track rails 6. The clips 21 are slidably mounted upon the track rails 6 and the guides 22 are pivotally connected with the said clips the bits 19 pass through the orifices 23 provided in the said guides 22. The shape of the bits 19 along the portions thereof which operate in the orifices 23 of the guides 22 is such as to cause the lower ends of the bits 19 to move obliquely with relation to the track rails 6 as the bars 10 are reciprocated. In order to accomplish this movement the said bits 19 turn axially at the joints 20 and consequently they work the ballast material under the tie 18 and pack the same immediately beneath the track rails 6.

It will be observed that the gear segments 14 may be engaged with the upper or lower teeth 4 of the rack standards 3 and when the segments 14 are engaged with the lower teeth of the said rack standards the bits 12 may be forced to operate at a greater depth below the surface of the track bed than when the said segments 14 are in mesh with the upper teeth of the said standards. Thus, provision is made for so positioning the parts with relation to each other as to cause the said bits to operate near or remote from the surface of the track bed.

Having described my invention, what I claim as new and desire to secure by Letters Patent is:

50 1. A tamping implement comprising a wheel mounted axle, rack standards supported upon the axle, bars mounted for reciprocation upon the axle, tamping bits carried by the bars, operating levers adjustably engaging the standards and means carried by the levers for engaging the bars.

2. A tamping implement comprising a wheel mounted axle, standards located upon the axle, rail clamps attached to the standards, bars mounted for reciprocation upon the axle, tamping bits carried by the bars, levers adjustably engaging the standards and means carried by the levers for engaging the bars.

65 3. A tamping implement comprising a

wheel mounted axle, a standard located thereon, a bar mounted for reciprocation upon the axle, a tamping bit carried by the bar, a lever adapted to adjustably engage the standard and means mounted upon the lever for engagement with the bar.

4. A tamping implement comprising a wheel mounted axle, standards located thereon, clamp members hingedly attached to said standards, bars mounted for reciprocation upon the axle, tamping bits carried by the bars, levers adapted to adjustably engage the standards and means mounted upon the levers for engagement with the bars.

5. In a tamping implement as described, tamping bits mounted for longitudinal reciprocation, means for operating the bits, track clamping members hingedly mounted upon the implement and a longitudinally extensible push bar adapted to operate at its ends against the track clamps.

6. In a tamping implement, a reciprocating bar, means for reciprocating the bar, a tamping bit pivotally mounted upon the bar and a guide adapted to engage a fixed object for directing said bit in its course of operation.

7. In a tamping implement, a bar mounted for reciprocation, means for reciprocating the bar, a tamping bit having ball and socket connection with said bar and a guide adapted to be attached to a fixed object for directing said bit in its course of operation.

8. In a tamping implement, a bar mounted for reciprocation thereon, means for operating the bar, a tamping bit carried by the bar and adapted to turn axially, a guide adapted to engage a fixed object and direct said bit in its course of operation.

9. In a tamping implement, a bar mounted for reciprocation, means for operating the bar, a bit carried by the bar and adapted to turn axially, a guide adapted to engage a track rail for directing the bit in its course of operation.

10. In a tamping implement, a bar mounted for reciprocation, means for operating the bar, a bit carried by the bar and adapted to turn axially, a guide slidably mounted upon the track rail and adapted to direct the bit in its course of operation.

11. A tamping implement comprising a reciprocating bar means for reciprocating the bar, tamping bits mounted upon the bar, some of said bits being arranged to operate upon material in lines parallel with the track while other bits are arranged to tamp material under the points of intersection of the track rail and tie.

12. A tamping implement comprising a bar mounted for reciprocation, means for reciprocating the bar, bits carried by the bar, some of those bits adjacent the track rails being arranged to operate in oblique courses with relation to the same.

13. A tamping implement comprising a reciprocating bar, bits carried thereby, a lever for operating the bar and having an adjustable engagement with the implement whereby the length of stroke of the bar and bits may be regulated.

14. A tamping implement comprising a bar mounted for reciprocation, bits carried by the bar, standards mounted upon the implement, a lever for operating the bar and being adjustably engaged with the standard whereby the stroke of the bar and the bits may be regulated.

15. In a tamping implement means for 5 operating upon material under intersecting portions of structure comprising a support, a tamping bit mounted thereon for reciprocatory movement and adapted to operate upon

the material occupying an area lying directly below the intersecting portions of the said 20 structure.

16. In a tamping implement means for 25 operating upon material under intersecting portions of structure comprising a support, a tamping bit mounted thereon for reciprocatory movement at an angle to and in a line intersecting a line depending at a right angle from the longitudinal axes of the portions of structure at the point of intersection thereof.

In testimony that I claim the foregoing as 30 my own, I have hereto affixed my signature in the presence of two witnesses.
